UNITED STATES PATENT OFFICE.

ELISHA B. NOEL, OF CORDELL, OKLAHOMA, ASSIGNOR OF ONE-HALF TO ELISHA W. CARLTON, OF CORDELL, OKLAHOMA.

COTTON-CHOPPER.

1,043,456.

Specification of Letters Patent.

Patented Nov. 5, 1912.

Application filed May 27, 1912. Serial No. 700,063.

To all whom it may concern:

Be it known that I, ELISHA B. NOEL, a citizen of the United States, residing at Cordell, in the county of Washita and State of Oklahoma, have invented certain new and useful Improvements in Cotton-Choppers, of which the following is a specification, reference being had to the accompanying drawings.

10 This invention comprehends certain new and useful improvements in cotton choppers and has for its object to provide an implement of this nature which will be simple in construction and cheap to manufacture.

15 Another object of the invention is to provide a machine to which cultivators may be easily attached so that cotton may be thinned and cultivated at the same time.

20 The invention also aims to generally improve implements of this nature to render them more efficient and commercially desirable.

With these and other objects in view, as shall become apparent as the description 5 proceeds, the invention consists in certain novel constructions and arrangement of parts as I shall hereinafter fully describe and claim.

For a complete understanding of my invention reference is to be had to the following description and accompanying drawing in which—

Figure 1 is a side elevation of my improved cotton chopper, one wheel thereof being removed. Fig. 2 is a top plan view of my invention. Fig. 3 is a detail perspective view of the flanged rim used in connection with my device. Fig. 4 is a detail perspective view showing the method of connecting the drive rods to the main frame. Fig. 5 is a perspective view of the secondary frame which supports the chopping pole. Fig. 6 is a detail front elevation of the carriage used to prevent the drive rods separating an undue distance.

Referring to the drawings by numerals 1 designates wheels rigidly secured to the axle 2.

3 is an essentially rectangular frame having the side bars 4 and end bars 5. The frame is secured near its rear end to the axle 2 by suitable boxings 6 and supports a seat 7. A tongue 8 is connected to the front of the frame by the hounds 9. Cultivator shovels 10 are secured to the down-

wardly extending brackets 11 which are fixed to the side bars 4 of the frame 3.

Runners 12, connected at their front ends in spaced relationship by the cross-bar 13, are detachably connected to the front bar 5 of the frame 3 by the hook 14 and chain 15. A frame 16 comprising the parallel cross-bars 17, the parallel longitudinal bars 18 and the parallel uprights 19 is secured at its front end above the runners 12 by the standards 20. A pair of brace bars 21 are bolted to the front ends of the runners 12, the standards 20 the longitudinal bars 18 and the rear uprights 19, holding the frame 16 firmly in position. The longitudinal bars 65 18, which are normally level with and parallel to the side bars 4 of the frame 3, have secured intermediate their ends the U shaped brackets 22. These brackets engage the side bars 4 to prevent lateral movement of the 70 frame 16, while allowing a vertical motion. A rotatable shaft 23 having a cross piece 24 formed on the rear end thereof is secured by the brackets 25 to the frame 16. A double edge hoe 26 is connected by the arm 27 to 80 the shaft 23 and is free to oscillate in a transverse vertical plane. A frame 28 is mounted on the hoe arm 27 and serves to prevent the cotton and weeds when cut from falling in the path of the cultivator shovels 10. 85

To actuate the hoe and cause it to swing from side to side I provide the drive rods 29 and flange wheel 30. The flange wheel 30 is rigidly secured to the axle 2 intermediate its ends and is provided with a removable 90 rim 31 having the angular flanges 32 formed on the edges thereof in staggered relationship. When it is desired to change the speed or frequency with which the hoe 26 oscillates the rim 31 is removed and another 95 having differently spaced fingers substituted.

The drive rods 29 which coöperate with the wheel 30 to actuate the hoe 26 are connected at their front ends to the hoe arm 27 100 and extend rearwardly in parallel spaced relationship on opposite sides of the wheel 30 and are connected at their rear ends to the levers 33, whose purpose will be explained later. A supporting rod 34 having 105 its ends secured in the frame 3 supports the rear ends of the drive rods 29. The front portions 35 of the rods 29 are closer together than the rear portions 36, there being just enough space between them to allow a 110

flange 32 to pass. When the beveled edge of one of the flanges 32 strikes a drive rod 29 it causes both rods and the hoe 26 to move toward one side of the frame 3. The succeeding flange being on the opposite side of the wheel 30 causes the drive rods 29 and hoe 26 to swing to the other side of the frame and thus a continuous oscillating motion of the hoe is obtained.

10 In order to prevent the front portions 35 of the rod 29 spreading when struck by the flanges 32 I provide a roller carriage 37 comprising two pieces 38 of flat metal having the longitudinal recesses 39 which are 15 open at their inner ends. A bolt 40 connects the pieces 38. Wheels 41, having grooved peripheries are journaled in the outer ends of the pieces 38 and run on the transverse spaced tracks 42. These tracks are supported at an angle to the horizontal plane 20 by the brackets 42'. The drive rods 29 pass through the recesses 39 and are prevented from spreading beyond a certain adjustable width by the end walls of said recesses.

25 The levers 33 are secured to the frame 3 by brackets 34' and have their arms 35 removably held to the frame by the locking rings 36. To spread the drive rods 29 so that they will not coöperate with the wheel 30 the lever arms 35 are swung downwardly and inwardly.

The shaft 23 is prevented from moving 35 too far forward or backward by the rods 43 which pivotally connect to the cross piece 24 and to the cross bar 44. The ends of said cross bar 44 are supported by brackets 45.

Levers 46 having hooks 47 formed on 40 their front ends and having their rear ends mounted on the cross bar 44. These levers are for the purpose of raising the runners 12. The hooks 47 engage under the lifting bar 50 which is secured to the brackets 22 45 and the bar 48 may be pressed downward by the foot of the operator.

In the operation of the machine described, the flanges 32 striking the driving rods 29 cause the hoe 26 to oscillate from side to side and cut the stalks of the cotton or other plants. The runners 12 counteract any slight unevenness of the ground and retain the hoe at the proper elevation for cutting. I have found that by mounting the hoe on 55 a secondary frame as described a much evener cutting action is secured than is the case when the hoe is carried by the main frame. In crossing from one field to another the runners 12 may be raised and the 60 hoe rendered inoperative in the manner previously described.

It will be understood that while I have shown a preferred form of my invention I do not limit myself to the precise construction shown and described, the scope of my

invention being clearly defined in the appended claims.

What I claim is:—

1. A cotton chopper comprising a main frame mounted on wheels, a secondary frame mounted on runners, flexible connections adapted to removably secure the forward end of the secondary frame to the forward end of the main frame, said secondary frame being adapted for vertical movement 70 independent of the main frame, a chopping bar mounted to swing on the secondary frame, means carried by the main frame for driving said chopping bar, and means carried by the secondary frame for preventing 80 lateral movement of said frames relative to each other.

2. In a cotton chopper, the combination of an axle, wheels rigidly secured to said axle, a frame mounted on the axle, a second 85 frame mounted on runners and connected to the first mentioned frame, a chopping bar mounted to swing on the latter frame, spaced longitudinally extending drive rods connected at their front ends to the chopping bar and at their rear ends to the first mentioned frame, and means carried by the axle for operating said drive rods.

3. In a cotton chopper, the combination of an axle, wheels rigidly secured on said axle, 95 a main frame mounted on said axle, a secondary frame supported on runners and connected to the main frame, a chopping bar mounted to swing on the secondary frame, spaced longitudinally extending 100 drive rods connected at their rear ends to the main frame and at their front ends to the chopping bar and a flanged wheel rigidly secured to the axle and adapted to alternately engage the drive rods.

4. In a cotton chopper, the combination with an axle, wheels rigidly secured to said axle, a main frame mounted on the axle, a secondary frame supported on runners and secured at its forward end to the forward 11 end of the main frame, a chopping bar mounted to swing on said secondary frame, spaced drive rods extending longitudinally of the machine and connected at their rear ends to the main frame and at their forward ends to the chopping bar, a flanged wheel rigidly secured to the axle and adapted to alternately engage the drive rods and means for preventing said drive rods spreading when acted on by the flanged wheel.

5. In a device of the class described, the combination of a main frame supported on wheels, a secondary frame supported on runners, flexible connections for securing the forward end of the secondary frame to the forward end of the main frame, guide brackets carried by the secondary frame, a transverse rod connecting said brackets, a U shaped lifting lever pivotally supported by the main frame and adapted to engage

under said transverse rod carried by the secondary frame for lifting the same, a chopping bar mounted to swing on the secondary frame and means for operating said chopping bar.

6. A cotton chopper comprising a main frame, a secondary frame, a chopping bar mounted to swing on said secondary frame, spaced drive rods extending longitudinally 10 of the machine and connected at their rear ends to the main frame and at their forward ends to the chopping bar, a flanged wheel rigidly secured to the axle of the main frame and adapted to alternately engage the drive rods, and a longitudinally adjustable roller carriage provided with a longitudinal slot through which said drive rods project, the carriage being adapted to prevent said drive rods spreading when acted upon by the flanged wheel.

7. A cotton chopper comprising a main frame, having an axle and supporting wheels

rigidly secured thereto, a secondary frame supported on runners and secured at its forward end to the forward end of the main frame, a chopping bar mounted to oscillate on the secondary frame, spaced longitudinally extending drive rods connected at their forward ends to the chopping bar, crank levers rotatably secured to the main frame and to which the rear end of the said drive rods are pivotally secured, and a flanged wheel rigidly secured to the axle and adapted to alternately engage the drive rods, said crank levers being adapted to 25 30 35 spread the drive rods so as to render the chopping bar inoperative.

In testimony whereof I hereunto affix my signature in the presence of two witnesses.
